UNITED STATES PATENT OFFICE.

SIMON EICHBERG, OF CHICAGO, ILLINOIS.

HOSE-SUPPORTER.

1,390,769.

Specification of Letters Patent. Patented Sept. 13, 1921.

Application filed November 29, 1918. Serial No. 264,608.

To all whom it may concern:

Be it known that I, SIMON EICHBERG, a citizen of the United States, and a resident of the city of Chicago, county of Cook, and 5 State of Illinois, have invented certain new and useful Improvements in Hose-Supporters, of which the following is a specification.

My invention relates to improvements in 10 hose supporters or garters and has for its object the provision of an improved construction of this character, which is readily adjustable, dispenses with the use of buckles, and is simple and efficient in use.

Other objects will appear hereinafter.

15 The invention consists in the combinations and arrangements of parts hereinafter described and claimed.

The invention will be best understood by 20 reference to the accompanying drawings forming a part of this specification, and in which—

Figure 1, is a face view of a supporter embodying the invention,

Fig. 2, side view thereof, and

25 Fig. 3, a view showing the supporter in position of use.

The form of construction illustrated in 30 Figs. 1, 2 and 3 comprises a strip 5 of elastic material adapted to be secured at its upper end to a corset, band, or other support. The strip 5 is provided on its outer side with a reinforcing strip 6, also of elastic, and a plurality of eyes 7 are secured to the strip 6, as shown. A wire loop 8 is secured to 35 the lower end of the elastic strip 5, and a tongue 9 of non-elastic cloth is also secured either to the loop 8 or to the lower end of the elastic 5. A hook 10 is secured to the upper free end of the tongue 9 and is adapted 40 to engage the eyes 7. A strip 11 of non-elastic material is also secured to loop 8 and is provided at its lower end with the usual hose fastener 12.

It will be observed that the strip 11 constitutes a tensile element fixed to the end 45 of the elastic strip so as to be incapable of movement relatively to the said strip during use. Likewise, the tongue 9 and hook

10 constitutes a fastening element also fixed to the end of the elastic strip and to the 50 corresponding end of the tensile element 11.

By this arrangement it will be observed that the length of the supporter may be readily adjusted by engaging the hook 10 with one of the eyes 7, thus forming a loop 55 13 in the elastic strip 5—6 which is relieved of all strain will lie flat against the person of the wearer. The construction set forth dispenses with the use of all buckles and employs only constructions which will lie 60 flat and be comfortable to the wearer.

While I have illustrated and described the preferred form of construction for carrying my invention into effect, this is capable of variation and modification without 65 departing from the spirit of the invention. I, therefore, do not wish to be limited to the precise details of construction set forth, but desire to avail myself of such variations and modifications as come within the scope of 70 the appended claim.

Having described my invention, what I claim as new and desire to secure by Letters Patent is—

A hose supporter comprising a strip of 75 elastic consisting of an inner wider strip and an outer narrower strip secured to the outer face of said wider strip; eyes arranged at intervals on the outer side of said narrower strip; a loop fixed to the lower end 80 of said elastic; a laterally extending tongue also fixed to the lower end of said elastic and having a hook at its free end adapted to engage said eyes; a tensile element in the form of a strip of non-elastic material fixed 85 to the lower end of said elastic strip; and a hose fastener at the lower end of said tensile element, substantially as described.

In testimony whereof I have signed my name to this specification in the presence of 90 two subscribing witnesses.

SIMON EICHBERG.
